UNITED STATES PATENT OFFICE

ADRIAN O. ABBOTT, JR., OF DETROIT, MICHIGAN, ASSIGNOR TO MORGAN & WRIGHT, OF DETROIT, MICHIGAN, A CORPORATION OF MICHIGAN

APPARATUS FOR MANUFACTURING TIRE CASINGS

Application filed September 24, 1928. Serial No. 308,091.

This invention relates to a machine for expanding automobile tires from the flat pulley band form to the normal tire shape and is an improvement over the device disclosed in my Patent No. 1,507,563, granted September 9, 1924.

It is the object of this invention to provide a new and efficient means for forming a seat between the pulley band and the apparatus for expanding the pulley band.

Without intending to limit my invention more than is required by the prior art and with the disclosed embodiment in mind, it consists broadly in providing a pulley band machine with tubular expansible rings positioned at the sides of the casing of the machine, which tubes may be expanded to admit the pulley band into the machine by introducing air under pressure within the tube, reduction of the air pressure allowing the tubes to contract so as to contact with the pulley band and form an air tight seal therewith.

A clear understanding of my invention may be had from the following detailed description and accompanying drawings in which:

Fig. 1 is an elevation of my machine;

Fig. 2 is a vertical central section through the upper portion of my machine;

Fig. 3 is a detailed view partly in section showing the construction of the expansible tube.

The pulley band 1 fits into the interior of the annular casing 2 which is made up of the annular side wall 3, top and bottom end walls 4 and 5 which have apertures therethrough to provide a central opening 6 through which the pulley band 1 extends. The pulley band 1 fits freely within the central opening 6 so that auxiliary means are necessary to form a seal between the casing and the pulley band during the shaping operation.

The tubes 7 positioned on each side of the casing 3 and held in sliding engagement therewith by the circular plates 8 serve as the means for forming a seal between the casing and the pulley band 1. These tubes 7 are made of rubber or other elastic material and are preferably made so as to permit expansion

along its longitudinal axis but not transversely of the tube, as for instance by embedding a cord or wire spiral 18 in the walls of the material. The plates 8 may be secured to the walls 4 and 5 of the annular casing 2 by posts 8a.

In order to admit the pulley band 1 to the casing 3 the circular tubes 7 may be expanded by introducing air under pressure therein from the pipe system 9 leading to a suitable source of pressure. The pipe system 9 is connected to the tubes 7 through the flexible tube 10, the purpose of which will later appear.

The casing is supported upon the pedestal 11 which also serves as a table upon which the lower edge of the pulley band 1 may rest when first inserted in the machine.

Suction is applied to the casing 3 through the pipe system 12 from any suitable source.

In order to permit the removal of the tire after it has been shaped, the upper end wall 4 is hingedly mounted as indicated at 13 on the side wall 3. A weighted system of levers 14, pivoted to the pedestal 11 as at 15 and to the upper side wall 4 as at 16, facilitates lifting of the lid 4 of the evacuating box and removal of the shaped tire. The flexible tube 10 connecting the pipe system 9 with the tubes 7 permits the rotation of the upper end wall 4 with respect to the casing.

In the operation of the machine pressure is applied through the pipe system 9 and tubes 10 to the circular tubes 7 thereby expanding them to a position such that the pulley band 1 may be more readily inserted within the casing or box 2. The pressure acting in tubes 7 is then released so that these tubes under their natural elasticity contract so as to contact with the pulley band 1 and form a seal therewith. Suction is then applied to the interior of the casing or box 3 through the pipe 12 to draw the pulley band from the flat shape shown in full lines in Fig. 1 to the shape shown in dotted lines in the same figure. As the pulley band changes shape under the action of the atmospheric pressure the contact between the pulley band and the tubes 7 serves as a seal during the initial changes in shape and the edges of

opening 6 contact with the pulley band to form a seal during the last stages of the shaping operation. A curing bag or other suitable agency is inserted within the tire in the usual manner, the upper side wall opened by means of the system of levers 14 and the casing and contained curing bag removed from the machine.

While one specific embodiment of my invention has been described in detail, other forms of my invention such as would occur to one skilled in the art are contemplated, and for an understanding of the scope of my invention reference should be made to the following claims.

Having thus described my invention, what I claim and desire to protect by Letters Patent is:

1. In a pulley band expanding machine in combination, an annular casing open on its inner periphery and adapted to receive a pulley band therewithin, a tube on each end of the casing circumferentially disposed with respect to the pulley band, and means for supplying air pressure to the tube to expand it.

2. In a pulley band expanding machine in combination, a rigid annular casing open along its inner periphery and adapted to receive a pulley band within the inner periphery, an expandible tube on each end of the casing and adapted to surround the pulley band and form a seal therewith, and means for expanding said tube to admit the pulley band.

3. In a pulley band expanding machine in combination, a non-collapsible annular casing open along its inner periphery and adapted to receive a pulley band within the inner periphery, an expandible tube on each end of the casing adapted to surround the pulley band and to form a seal therewith; said tube being expandible longitudinally but not transversely, and means for expanding said tube to admit the pulley band.

4. In a pulley band expanding machine in combination, a non-collapsible annular casing open along its inner periphery and adapted to receive a pulley band therewithin, an expandible tube on each end of the casing arranged to surround the pulley band and to form a seal therewith, said tube having a spirally wound cord therewithin to permit longitudinal expansion and to prevent transverse expansion; means for supplying air under pressure to said tubes to expand the same, and means for exhausting the air from the casing.

Signed at Detroit, county of Wayne, State of Michigan, this 18th day of September, 1928.

ADRIAN O. ABBOTT, JR.
